United States Patent

Des. 238,577

Patented Jan. 27, 1976

238,577

TOILET

Clifford Bruce Hewson, Toronto, Ontario, Canada, assignor to Sanitation Equipment Limited, Downsview, Ontario, Canada

Filed July 29, 1974, Ser. No. 492,959

Term of patent 14 years

Int. Cl. D23—02

U.S. Cl. D23—48

FIG. 3

FIG. 1 is a perspective view taken from the front, top and left side of a toilet showing my new design;

FIG. 2 is a perspective view taken from the rear, bottom and right side thereof; and

FIG. 3 is a perspective view taken from the front, top and right side thereof.

I claim:

The ornamental design for a toilet, as shown.
